UNITED STATES PATENT OFFICE.

CLIFTON BURT CORELL, OF NEW YORK, N. Y., ASSIGNOR TO GRAFF, WASHBOURNE & DUNN, OF NEW YORK, N. Y., A CORPORATION OF NEW YORK.

ADDING AND LISTING MACHINE.

Application filed August 12, 1921. Serial No. 491,679.

To all whom it may concern:

Be it known that I, CLIFTON BURT CORELL, a citizen of the United States of America, and a resident of the city of New York, borough of Manhattan, and State of New York, have invented certain new and useful Improvements in Adding and Listing Machines, of which the following is a specification.

10 This invention relates particularly to a machine for listing amounts which are being added on an adding machine of a type that comprises a series of computing mechanisms each consisting of a pair of wheels connected by an endless chain the adding being effected by drawing on the chains with a stylus. The listing machine is organized as an attachment so that the adding machine may be operated and will function 15 properly either with or without the connection with the listing machine.

The object of this invention is to provide a listing machine of this character of reliable and substantial construction and in 20 compact form.

In the accompanying four sheets of drawings which form a part of this specification:—

Figure 1 is a side elevation with the frame 30 broken away of a listing machine which embodies this invention together with an adding machine through which the listing machine is operated.

Fig. 2 is a plan of the adding and listing machine with the frame of the adding machine broken away.

Fig. 3 is a plan of the listing machine with the frame in section.

Fig. 4 is a transverse section on the line 40 IV—IV of Figs. 1 and 3 showing the inking rollers.

Fig. 5 is a transverse section on the line V—V of Figs. 1 and 3 showing the listing wheels in section.

45 Fig. 6 is a transverse section on the line VI—VI of Figs. 1 and 3 showing the sprocket connections between the adding machine and the listing wheels and the disconnecting mechanism.

50 Fig. 7 shows the connection between the operating lever and the printing rod and the feed rod.

The listing machine is illustrated in association with an adding machine in which 55 there is a series of computing wheels 10, 10

and a series of reset wheels 11, 11. Chains 12, 12 connect the computing and reset-wheels. A computing wheel, corresponding reset wheel and connecting chain constitutes one of the series of computing mechanisms 60 of successive denominations, and each computing mechanism except the one to the extreme left is a lower computing mechanism with respect to the one to the left which is the next higher computing mechanism. The computing wheels of the lower computing mechanisms carry pawls, 13, 13 through which connection is made with the computing wheels of the next higher computing mechanisms for carrying. The computing wheels have digits inscribed on their peripheries which show the totals and the wheels are mounted on a fixed shaft 14. Flanged disks 15, 15 pinned to the shaft, 65 separate the wheels. The carrying pawls 70 travel within the flanges which have openings through which the pawls protrude for engagement with the teeth of the next wheel for carrying.

The reset wheels carry reset lugs 16, 16 75 and revolve on a shaft 17 which is grooved longitudinally to receive a comb 18. The comb can be shifted longitudinally to bring its teeth into the paths of the lugs and the shaft turned by a crank 19 to reset the mechanisms. This adding mechanism constitutes 80 in itself a complete operative device and for further details which are applicable to it reference is made to my copending application filed concurrently herewith, Serial No. 491,678. 85

Mechanism constituting the listing machine is carried in a separate frame from the frame in which the adding mechanism is carried so that the two can be readily separated. The two frames are of the same 90 lengths and widths where they come together and are adapted to fit together, the listing machine being placed under the adding machine.

A series of listing mechanisms corresponding to the series of computing mechanisms of the adding machine include listing wheels 20, 20, and sprocket wheels 21, 21 through which the listing wheels are connected to the lower runs of the adding machine chains. Gears 22, 22 are attached to the sprocket wheels and engage gears 23, 23 which are attached to the listing wheels.

Disconnecting fingers 24, 24 lie along side 100 105 110

of the sprocket wheels and when lifted raise the chains out of engagement with the sprockets. The points of connection are preferably about midway of the runs of the 5 chains and the chains have sufficient slack to permit the required amount of deflection. The sprocket wheel of each lower computing mechanism as it turns engages a pin 25 which projects from the disconnecting finger 10 of the next higher computing mechanism and corresponding listing wheel, lifts this finger and disconnects this computing mechanism and listing wheel so that if there should be a carry, the carry will not be communicated to the listing mechanism. A pin 15 26 is carried by the disconnecting finger of each lower computing mechanism and underlies the disconnecting finger of the next higher computing mechanism. In consequence, when any finger is lifted, all of the 20 fingers to the left are also lifted, and all of the higher computing mechanisms are disconnected from their corresponding listing wheels so that in event of a carry extending 25 through several higher computing mechanisms it will not be communicated to any of the corresponding listing wheels. As soon as the sprocket by which a finger is lifted stops turning the fingers fall back by gravity and the pin by which the finger was 30 lifted drops back into a notch in the sprocket wheel.

Provision is also made for disconnecting all of the computing mechanisms from the 35 listing wheels during resetting of the computing mechanisms through the disconnecting fingers. They are all mounted on a shaft 27 and the first disconnecting finger has a rearwardly projecting arm 28 which 40 is carried to the outside of the frame through a slot 29 in the frame and its tip engages a notch 30 in the hub of the resetting crank when the crank is in normal position. As soon as the crank starts to turn 45 the tip of the arm is forced out of the notch, all of the disconnecting fingers are lifted and the computing and listing mechanisms are completely disengaged from each other. When the crank has been turned a full turn 50 to effect resetting, the arm reengages the notch and the disconnecting fingers fall back and permit the chains to again engage the sprocket wheels.

The listed number is printed on a strip of 55 paper which is fed from a reel 31, each trunnion of which rests in a notch 31^a to permit removal of the reel. The paper is led between feed rolls 32, 33 and between a platen 34, which consists of a sheet-metal holder 34 and a pad 34^a, and the under side of the listing wheels, and out through a slot 34^b. The platen is pivoted at 35 and presses the paper against the listing wheels on drawing forward an operating lever 36, from the normal 60 position shown in Fig. 1. The operating

lever is fast on a shaft 36^a as is also a two-arm member 36^b. A printing rod 37 connected with this lever through the two-arm member carries a lug 38 which is beveled on both its upper and under sides and is located 70 so that on initial movement of the operating lever it will ride over a prong 39 attached to the platen and cause the platen to press the paper against the listing wheels. On the return movement the lug passes under the 75 prong and the platen is not pressed against the listing wheels. The prong is pivoted to the platen so that it has a slight vertical movement independently of the platen to let the lug pass either above or below it. The 80 printing rod is guided by the platen pivot which passes through a slot in the rod and also by a projecting pin 37^a from the rod which travels in a slot in the side of the supporting frame. A feed rod 40, connected 85 with the operating lever through the two-arm member, carries a pawl 41 which engages a ratchet 42 attached to one of the feed rolls, and feeds the paper during the latter 90 part of the forward movement of the operating lever. The side of this pawl is in frictional engagement with the side of the supporting frame and is thereby rocked into engagement with the ratchet on forward movement of the feed rod, and is rocked out of 95 engagement with the ratchet when the feed rod is drawn back. Engagement and feeding does not commence until there has been sufficient movement to effect the printing. A lever 43 engages this rod and a spring 100 100 bears against the lever and effects the automatic return of the operating lever and connected parts. The tip of this lever passes through a slot near the end of the feed rod and travels in a slot in the side of the supporting frame and the feed rod is thereby 105 guided.

The sprocket wheels and attached gears turn on a shaft 45, and this shaft is carried in a frame 46 pivoted at 47 so that by 110 rocking this frame the gears between the sprocket wheels and the listing wheels can be separated. The gears are held in engagement by a projection 48 on the feed rod when the operating lever is in its normal position. When the operating lever is drawn forward the projection from the feed rod is moved away and separation of the gears is effected by a spring 49. This permits resetting of the listing wheels without 115 the movement being transmitted to the adding mechanism.

The listing wheels have reset lugs 50, 50 and are mounted on a reset shaft 51 with reset pins 52, 52. A comb 53 normally 120 locates the wheels so that the reset pins will not be in the paths of the lugs when the listing wheels are being set for listing, but on drawing forward the operating lever far enough to complete the printing and release 125 130

of the platen, on further movement a cam 54 on the end of the comb is engaged and the comb and gears shifted so as to bring the reset lugs carried by the listing wheels into 5 the paths of the reset pins on the shaft. On further forward movement of the operating lever a segment 55 is engaged and in mesh with the segment is a pinion 56 on the reset shaft through which the shaft is rotated and 10 the listing wheels are reset.

On return of the operating lever the segment is returned to its initial position, the shaft on which the listing wheels are mounted is turned back to its initial position, a 15 bell-crank 57 is engaged by the operating lever and through it the comb is shifted back thereby returning the listing wheels to their original position, and the projection on the feed rod returns into engagement 20 on the feed rod returns into engagement the gears between the sprockets and listing wheels so that the listing wheels are again connected through the sprockets with the chains and will again be set on operation of the adding machine.

25 Inking of the listing wheels is effected by inking rollers 58, 58, of which there is one for each listing wheel. These rollers are carried in bell-crank frames 59, 59 and drawn against the listing wheels by springs 30 60, 60. The listing wheels are formed with type faces on their peripheries, and notches between the type faces, and the inking rollers are positioned so that each will rest in a notch and serve to locate the wheel with 35 one of the type in printing position. The bell-crank frames are mounted on a plate 61 which is hinged at 62 so that it can be turned out and carry the inking rollers with it to an accessible position for reinking.

40 Legs 63, 63 are hinged at one end of the bottom and may be turned out to the position indicated in dotted lines so that the adding and listing machine can rest on a table at a convenient angle for use. A cover 45 64 which is hinged at the opposite end of the frame from the legs can be closed with the legs either folded into grooves in the frame as shown in full lines or folded out as shown in dotted lines and it secures the 50 legs in either position. The cover is a sufficiently snug fit in the supporting frame so that it will not open accidentally.

When the cover is lifted access may be had to the reel which carries the roll of 55 paper. A gear 65 on the reel spindle meshes with a gear 66 which projects through the supporting frame where it can be engaged by the thumb of the operator to adjust the paper on the reel or to coil a 60 new supply thereon.

I claim—

1. In a listing machine adapted for association with an adding machine which comprises a series of computing mechanisms of successive denominations and carrying 65

devices through which each lower computing mechanism operates the next higher computing mechanism, the combination of a series of listing mechanisms of successive denominations, connections between each computing mechanism and the corresponding listing mechanism, and means operating with the operation of each lower computing mechanism and its connected listing mechanism to effect the disconnection of the 70 higher computing and listing mechanisms.

2. In a listing machine adapted for association with an adding machine which comprises a series of computing mechanisms of successive denominations each consisting 75 of a pair of wheels connected by an endless chain and carrying devices through which each lower computing mechanism operates the next higher computing mechanism, the combination of listing wheels, a sprocket 80 connection between the chain of each computing mechanism midway of one of its runs and the corresponding listing wheel, and means operating with the operation of each lower computing mechanism and its connected listing mechanism to lift the chains of the higher computing mechanisms from the sprocket connections with their corresponding listing wheels.

3. In a listing machine adapted for association with an adding machine which comprises a series of computing mechanisms of successive denominations with reset wheels and a reset shaft therefor, the combination of a series of listing mechanisms of successive denominations, connections between each computing mechanism and the corresponding listing mechanism, and means operating with the reset shaft to effect the disconnection of the computing 95 and listing mechanisms.

4. In a listing machine adapted for association with an adding machine which comprises a series of computing mechanisms of successive denominations each consisting of 100 a pair of wheels connected by an endless chain, one of the wheels of each pair being a reset wheel and having a reset shaft therefor, the combination of listing wheels, a sprocket connection between the chain of each computing mechanism midway of one of its runs and the corresponding listing wheel, and means operating with the reset shaft to lift the chains of the computing 110 mechanisms from the sprocket connections.

5. In a listing machine adapted for association with an adding machine which comprises a series of computing mechanisms of successive denominations each consisting of 115 a pair of wheels connected by an endless chain, one of the wheels of each pair being a reset wheel and having a reset shaft therefor, and carrying devices through which each lower computing mechanism operates the next higher computing mechanism, the 120 125

combination of listing wheels, a sprocket connection between the chain of each computing mechanism midway of one of its runs and the corresponding listing wheel, means 5 operating with the operation of each lower computing mechanism and its connected listing mechanism to lift the chains of the higher computing mechanisms from the sprocket connections with the corresponding listing 10 wheels, and means operating with the reset shaft to lift the chains of the computing mechanisms from the sprocket connections.

6. In a listing machine, a series of listing wheels with reset lugs, a reset shaft with re- 15 setting pins on which the listing wheels are mounted, a comb for sliding the wheels longitudinally on the shaft and shifting the reset lugs into and out of the paths of the pins, a segment and pinion through which 20 movement is imparted to the reset shaft, an operating lever, connections between the operating lever and the comb for shifting the reset lugs into the paths of the resetting pins during its initial forward movement and 25 out of the paths during its final return movement, and connections between the operating lever and the segment for effecting the resetting of the listing wheels during its terminal forward movement.

30 7. In a listing machine, a series of listing wheels with reset lugs, a reset shaft with re- 35 setting pins on which the listing wheels are mounted, a comb for sliding the wheels longitudinally on the shaft and shifting the reset lugs into and out of the paths of the

pins, a segment and pinion through which movement is imparted to the reset shaft, an operating lever having a movement trans- 40 verse to the movement of the comb, a cam through which the comb is shifted in one direction by the operating lever, a bell- 45 crank lever through which the comb is shifted in the opposite direction by the operating lever, and connections between the operating lever and the segment for effect- 45 ing the resetting of the listing wheels.

8. In a listing machine adapted for association with an adding machine which comprises a series of computing mechanisms of successive denominations, the combination 50 of a series of listing wheels, a gear connecting each computing mechanism with the corresponding listing wheel, a reset shaft, a segment and pinion through which movement is imparted to the reset shaft, an operating 55 lever, connections between the operating lever and the segment for effecting the resetting of the listing wheels, and connections from the operating lever for effecting the separation between the listing wheels and 60 gear connections with the adding machine.

9. In a listing machine, a series of listing wheels with type faces on their peripheries and notches between the type faces, and a spring pressed inking roller for each wheel, 65 the roller being positioned so as to rest in a notch and serve to locate the wheel with one of its type in printing position.
